UNITED STATES PATENT OFFICE

2,030,095

FASTENER

Daniel A. Brennan, Chicago, Ill.

Application January 2, 1931, Serial No. 506,039

27 Claims. (Cl. 24—153)

The invention relates generally to improvements in fasteners for binding paper together, such as letters in a file; and more particularly to a new and improved fastener including a base having spaced prongs at its ends adapted to extend through apertures in the papers, and a compressor having similarly spaced apertures adapted to receive said prongs, the ends of the latter being adapted to be bent downwardly and 10 clamped to said compressor.

An object of the invention is to provide an improved fastener of the type referred to, which is more efficient in use and is simpler and quicker to manipulate than prior structures.

15 Another object is to provide the compressor with novel latches which are readily rotatable over the bent down prongs at or near their lines of bend.

Another object is to provide the compressor 20 with novel latches which are adapted to rotate over the prongs when the latter are bent down flat, either outwardly or inwardly of the compressor.

Another object is to provide the compressor 25 with novel latches which are readily rotatable over the bent down prongs when the latter are bent either outwardly or inwardly of the compressor, said latches being arranged to remain yieldably in position, ready to be rotated over 30 said prongs.

Another object is to provide means on the latches for binding the prongs to the compressor.

Other objects and advantages will become 35 more apparent as the description proceeds, taken with the accompanying drawing, in which:

Fig. 1 is a top plan view of the improved fastener, shown attached to a binding folder.

Fig. 2 is a fragmental longitudinal sectional view, taken on line 2—2 of Fig. 1.

40 Fig. 3 is a fragmental view of the fastener illustrated in Figs. 1 and 2, showing the prongs bent inwardly.

Fig. 4 is a plan view of another modified form of fastener, in binding position.

45 Fig. 5 is a plan view of the fastener shown in Fig. 8, in open position.

Fig. 6 is a plan view of another modified form of fastener.

50 Referring to Figs. 1, 2, and 3 of the drawing particularly, the fastener constituting one embodiment of the invention comprises a base 16 provided on its ends with spaced prongs 17, adapted to pass through similarly spaced perforations in the papers (not shown). Preferably,

the prongs 17 are substantially less in width than the body of said base and are struck up substantially at right angles thereto.

The base 16 normally is positioned to lie flush against the bottom of the file papers, or be secured to a backing sheet 18, and a compressor 19 formed with perforations 21, preferably round or arcuate, in opposite ends, for receiving the latches 22 and the prongs 17, is adapted to be placed against the top of the file papers, or secured to a backing sheet 18a. The rotatable latches 22 are arranged on opposite ends of the compressor for movement over the prongs when the latter are bent down against the compressor. These latches preferably are secured to the compressor by bushings or hollow rivets 23 extending through axially aligned openings in the latches and compressor. The ends of the bushings are flanged and lie against the latches on one side, and the compressor on the other, to hold them operatively together. To use this compressor as a permanent part of a binding folder, such as shown at 18—18a, the bushings are elongated and extend through the folder portion 18a, and the flanges then lie against the latches and binder.

Each latch 22 preferably is provided with an elongated lip 24. The corners 25 of said lips preferably are turned up to facilitate easy engagement of the latter over the bent down prongs. 30 A depression is also provided on the opposite end from the lip on each latch, such as at 26, to engage selectively with complementary depressions 27, one inwardly and one outwardly of each opening in the compressor to retain the latch 35 yieldingly in place. The compressor 16 is provided with struck up portions 28 to provide retaining elements to hold the latches bound to the bent down prongs, thus providing positive locking means.

The base 16 preferably is provided with tangs 29 which may be pressed through and engaged against a backing member, such as that shown at 18 in Fig. 2, or they may be left flat in the base to use against file papers without piercing a back- 45 ing sheet.

The form of fastener illustrated in Figs. 4 and 5 comprises a two part compressor 19a pivotally connected at the center and having spaced openings 21a, preferably circular, one at each end, 50 and a base having spaced prongs 17, adapted to extend through said openings and be bent downwardly against the compressor. The ends of the compressor are provided with lips 22a to form latches to bind the prongs to the compressor. 55

A plate 32 may be connected or secured to the bottom of the compressor to provide means to hold the parts of the compressor in alignment during the operations of moving the compressor 5 to engage or disengage the locks from the prongs. The plate 32 may be dispensed with in some instances.

The form of fastener shown in Fig. 6 is substantially similar to that shown in Figs. 4 and 5, 10 except that in this instance, the prongs 17d are adapted to be bent inwardly toward each other, and the latches 22b are arranged to engage said prongs in that bent down position.

Although various exemplary forms of the improved fastener have been illustrated in the accompanying drawing and described in detail in the foregoing specification, it is obvious that features of the present invention may be incorporated in other fasteners of the general type 20 shown, or otherwise varied in structural detail and arrangement without departing from the spirit of the invention and the scope of the appended claims.

I claim:

25 1. In a paper fastener, in combination, an elongated member having an opening at each end adapted to each receive a prong, latches mounted one in each opening for movement one over each of said prongs, a lip on each lock, and a flared portion on each lip adapted to facilitate movement of said latches into position over the respective prong.

30 2. In a paper fastener, in combination, an elongated member having an opening at each end adapted to receive a prong, latches mounted one in each opening for movement one over each of said prongs, and a lip on each latch.

35 3. In a paper fastener, in combination, an elongated member having an opening at each end adapted to each receive a prong, latches mounted one in each opening for movement one over each of said prongs, a lip on each latch, and co-operating means on said member and on said latches adapted to retain said latches in position over 40 the respective prong.

45 4. A paper fastener comprising, in combination, a compressor having spaced openings one in each end, an elongated base having spaced prongs one on each end, said prongs being adapted to be inserted through said openings and then bent down against said compressor, and locking means mounted in said openings adapted to rotate over said prongs in bent down position, said rotation being through a plane substantially parallel with said bent down position of said prongs.

50 5. A paper fastener comprising, in combination, a compressor having spaced openings one in each end, an elongated base having spaced prongs one on each end, said prongs being adapted to be inserted through said openings and then bent down against said compressor, retaining means on said compressor, and locking means on said compressor adapted to rotate about said openings over said prongs in bent down position 55 into engagement with said retaining means, said rotation being through a plane substantially parallel with said bent down position of said prongs.

60 6. A paper fastener comprising, in combination, a compressor having spaced openings one in each end, an elongated base having spaced prongs one on each end, said prongs being adapted to be inserted through said openings and then bent down against said compressor, and latches 65 on said compressor one rotatably mounted in

each of said openings, one adapted to move over each of said prongs in bent down position.

7. A paper fastener comprising, in combination, a compressor having spaced openings one in each end, an elongated base having spaced prongs one on each end, latches on said compressor one mounted in each of said openings, each latch having an opening in axial alignment with the associated opening in said compressor, said prongs being adapted to be inserted through said openings and then bent down against said compressor, and means on said latches to engage over said prong when said latches are moved about their mountings.

8. A paper fastener comprising, in combination, a compressor having spaced openings one in each end, an elongated base having spaced prongs one on each end, said prongs being adapted to be inserted through said openings and then bent down against said compressor, latches on 15 said compressor one rotatably mounted in each of said openings, one adapted to move over one of said prongs in bent down position, and means to retain yieldingly said latches in position over 20 said prongs.

9. A paper fastener comprising, in combination, a compressor having an opening, a base having a prong insertable through said opening adapted to be bent down over said compressor, and means rotatable in the plane of the keeper 30 mounted in said opening adapted to engage said bent down prong to retain said tongue in position.

10. A paper fastener comprising, in combination, a compressor having an opening, a base having a prong adapted to be inserted through said opening and bent down over said compressor, and means in said opening rotatable in the plane 35 of the keeper adapted to engage over said bent down tongue to retain said prong in position.

11. A paper fastener comprising, in combination, a compressor having spaced openings one in each end, a base having spaced prongs one on each end, latches on said keeper, one mounted in each of said openings, each of said latches 45 having an opening in axial alignment with the opening in which it is mounted, said prongs being adapted to be inserted through said axially aligned openings and then bent down against the compressor, a lip on each latch adapted to move over the respective prong in bent down position 50 when the latches are moved about their mountings, and an upwardly flared portion on each of said lips adapted to facilitate movement of the lips over the respective underlying prong.

12. A paper fastener comprising, in combination, a compressor having spaced openings one in each end, a base having spaced prongs one on each end, latches on said compressor, said prongs being adapted to be inserted one through each of said openings and then bent down against the compressor, a lip on each latch adapted to move over the respective prong in bent down position upon movement of the latches, and an upturned portion on each of said lips adapted to 60 facilitate movement of the lips over the respective underlying prong.

13. A paper fastener comprising, in combination, a compressor having an opening, a base having a prong adapted to be inserted through said opening and bent down over said compressor, and rotatable means mounted in said opening adapted 70 to engage over said bent down prong to retain said prong in position.

14. A paper fastener comprising, in combina- 75

tion, a compressor having spaced openings one in each end, a rotatable element mounted in each of said openings, said rotatable elements each having an opening in axial alignment with the respective opening in said keeper, a base having spaced prongs one on each end, said tongues being adapted to be inserted through said openings and then bent down substantially flat, and means on said aligned rotatable elements adapted 10 to engage over said bent down prongs to retain said prongs substantially flat.

15. A paper fastener comprising, in combination, a plate having spaced openings one in each end, a two part latch, one part pivotally mounted at one end in each of said openings, the opposite end of said latch parts being movably guided in said plate, a base having spaced prongs one on each end, said tongues being adapted to be inserted through said openings and then bent down 20 against said latch parts inwardly of the openings, and means on said latch parts to engage in unison over said bent down prongs.

16. A paper fastener comprising, in combination, a compressor having spaced openings one 25 in each end, an elongated base having spaced prongs one on each end, said tongues being adapted to be inserted one through each of said openings and then bent down against said compressor, latching means mounted in said openings adapted to rotate over said prongs in bent 30 down position, and means on said latching means to engage beneath means on said compressor upon engagement of said latching means over said prongs.

35 17. A paper fastener comprising, in combination, a compressor having spaced openings one in each end, an elongated base having spaced prongs one on each end, said tongues being adapted to be inserted one through each of said 40 openings and then bent down against said compressor, latching means mounted in said openings adapted to rotate over said prongs in bent down position, and means on said latching means to engage beneath means on said compressor upon 45 engagement of said latching means over said prongs, said rotation being through a plane substantially parallel with said bent down position of said prongs.

18. A paper fastener comprising, in combination, a compressor having spaced openings one in each end, an elongated base having spaced prongs one on each end, said tongues being adapted to be inserted one through each of said openings and then bent down against said compressor, 55 double walled latches on said compressor adapted to rotate one around each of said openings with one wall of each locking means over the underlying prong to bind the respective tongue to said compressor, said rotation being through a plane substantially parallel with said bent down position of said prongs.

50 19. A paper fastener comprising, in combination, a compressor having spaced openings one in each end, a base having spaced prongs, said 60 tongues being adapted to be inserted one through each of said openings and then bent down against said compressor, rotatable locks on said keeper, one adapted to move over one of said prongs in bent down position, and means to retain yield- 65 ingly said latches in position over said prongs.

70 20. A paper fastener comprising, in combination, a compressor having spaced openings one in each end, a base having spaced prongs, said 75 tongues being adapted to be inserted one through each of said openings and then bent down against

said compressor, rotatable latches on said compressor, one adapted to move over one of said prongs in bent down position, and means on the compressor and on each latch adapted to co-operate to retain yieldingly said latches in position 5 over the prongs.

21. A paper fastener comprising, in combination, a compressor having spaced openings, one in each end, a base having spaced prongs one at each end, said tongues being adapted to be inserted through said openings and then bent down 10 against said compressor, latching means on said keeper adapted to rotate about said openings over said prongs in bent down position, means to retain the latching means in position over said 15 prongs, and means to hold said latching means tightly against the prongs to hold said prongs flat against the compressor.

22. A paper fastener comprising, in combination, a compressor having spaced openings one 20 in each end, a base having spaced prongs one on each end, latches on said compressor one mounted in each of said openings, each of said latches having an opening in axial alignment with the opening in which it is mounted, said prongs being 25 adapted to be inserted through said axially aligned openings and then bent down against the compressor, a lip on each latch adapted to move over the respective prong in bent down position when the latches are moved about their mounting, an upwardly flared portion on each lip adapted to facilitate movement of the lips over the respective underlying prong, and means to retain said lips in position over said prongs.

30 23. In a paper fastener, in combination, an 35 elongated member having an opening at each end adapted to receive a prong, latches mounted one in each of said openings for rotation into and out of engagement with said prongs, and retaining elements on the elongated member one 40 adapted to co-operate with and hold each of said latches in position over the respective prong.

24. In a paper fastener, in combination, an 45 elongated member having an opening at each end adapted to receive a prong and a depression adjacent each opening, latches mounted one in each of said openings for rotation into and out of engagement with said tongues, and a projection on each latch adapted to engage in the respective depression to retain the latch in position over 50 the respective prong.

25. In a paper fastener, in combination, an 55 elongated member having an opening at each end adapted to each receive a prong, latches mounted on said member, for movement into and out of engagement one over each of said prongs, a lip on each latch, and a flared portion on each lip adapted to facilitate movement of said latches into engagement over the respective prong.

60 26. A paper fastener comprising, in combination, an elongated plate having spaced openings one in each end and a slot intermediate said openings, a two part latch, each of said parts having an opening at one end in axial alignment with and rotatably mounted in said openings in said 65 plate, the opposite ends of said latch parts being movably connected with said slot, a base having spaced prongs one on each end, said prongs being adapted to be inserted through said aligned openings and then bent down against the latch 70 parts, and means on said latch parts adapted to move in unison over said prongs in bent down position.

27. A paper fastener comprising, in combination, a plate having spaced openings one in each 75

end, a two part latch, each of said parts being rotatably mounted at one end on said plate, the opposite ends of said parts being movably connected with said plate, a base having spaced prongs one on each end, said tongues being adapted to be inserted through the openings in

said plate and then bent down against the latch parts, and means on said latch parts adapted to move in unison over said prongs in bent down position.

DANIEL A. BRENNAN.
